(57) **CLAIM**

The ornamental design for a enteral syringe, as shown and described.

DESCRIPTION

FIG. 1 is a front perspective view of the enteral syringe of the present invention showing our new design with the dotted lines depicting solely environmental structure and forming no part of the claimed design;

FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof;

FIG. 7 is a perspective view depicting the enteral syringe with its top cap disposed in an open configuration with the dotted lines depicting solely environmental structure and forming no part of the claimed design; and,

FIG. 8 is a perspective view depicting the enteral syringe with its removable top cap separated from the enteral syringe body with the dotted lines depicting solely environmental structure and forming no part of the claimed design.
